(57) **CLAIM**

The ornamental design for a base layer garment for use in hazardous environments as shown and described.

DESCRIPTION

FIG. 1.1 is a front view of a base layer garment for use in hazardous environments in a first embodiment showing my new design.

FIG. 1.2 is a front perspective view thereof.

FIG. 1.3 is a rear view thereof.

FIG. 1.4 is a rear perspective view thereof.

FIG. 4.1 is a front perspective view showing a second embodiment in which the shirt is shown tucked into the pants.

FIG. 4.2 is a rear perspective view thereof.

The thin lines in the figures represent surface contours only and do not illustrate ornamentation or indicia on the surface of the product.

1 Claim, 6 Drawing Sheets
